(57) CLAIM

The ornamental design for a shoe as shown and described.

DESCRIPTION

FIG. 1 is a bottom front perspective view of a shoe showing my new design;

FIG. 2 is a bottom view thereof; and,

FIG. 3 is a bottom rear perspective view thereof.

The broken lines immediately adjacent to the shaded area define the bounds of the claimed design and form no part thereof. The broken line showing of the tread in the front row forms no part of the claimed design. The broken line showing of the circular region on each tread forms no part of the claimed design. The broken line showing of the two rectangular strips form no part of the claimed design. The broken lines depicting the remainder of the shoe form no part of the claimed design.
